[57] CLAIM

The ornamental design for a gear shifting console for a bicycle, as shown.

DESCRIPTION

FIG. 1 is a perspective view of a gear shifting console for a bicycle, showing our new design;

FIG. 2 is a rear elevational view thereof;

FIG. 3 is a front elevational view thereof;

FIG. 4 is a top plan view thereof;

FIG. 5 is a right side elevational view thereof; and

FIG. 6 is a left side elevational view thereof, opposite that shown in FIG. 5.
